(57) **CLAIM**

The ornamental design for a removable floor outlet cover for integration with flooring, as shown and described.

DESCRIPTION

FIG. 1 is a front upper non-exploded perspective view of a removable floor outlet cover for integration with flooring of Applicant's design showing the cover inserted into its support frame;

FIG. 2 is an exploded view thereof showing the cover removed from its support frame showing its intended use to cover an outlet underlying the cover;

FIG. 3 is a top non-exploded elevational view thereof intended to face the same direction as the floor surface;

FIG. 4 is a bottom non-exploded elevational view thereof intended to face the opposite direction of the floor surface;

FIG. 5 is a first end non-exploded elevational view thereof as viewed from the left of FIG. 3;

FIG. 6 is a second end non-exploded elevational view thereof, the second end elevational view being opposite the first end elevational view and viewed from the right of FIG. 3;

FIG. 7 is a first side non-exploded elevational view thereof as viewed from the top of FIG. 3; and,

FIG. 8 is a second side non-exploded elevational view thereof, the second side elevational view being opposite the first side elevational view and viewed from the bottom of FIG. 3.

The dashed lines illustrate portions of the removable floor outlet cover for integration with flooring that form no part of the claimed design. The appearance of any portion of the removable floor outlet cover for integration with flooring between the dashed lines forms no part of the claimed design.

The dot-dashed lines in FIG. 2 show an outlet underlying the cover as an environmental structure. The underlying outlet shown in dot-dashed lines is for illustrative purposes and forms no part of the claimed design.

The dot-dot-dashed lines in FIG. 2 are projected lines that show the cover removed and detached from the support frame.
